UNITED STATES PATENT OFFICE.

RUDOLPH MEYER, OF NEW YORK, N. Y.

DESIGN FOR AN INCANDESCENT-LAMP SOCKET.

SPECIFICATION forming part of Design No. 32,003, dated December 19, 1899.

Application filed October 30, 1899. Serial No. 735,319. Term of patent 7 years.

To all whom it may concern:

Be it known that I, RUDOLPH MEYER, a citizen of the United States, and a resident of the city of New York, borough of Brooklyn, in the county of Kings and State of New York, have invented and produced a new and original Design for an Incandescent-Lamp Socket, of which the following is a full, clear, and exact description.

Reference is to be had to the accompanying drawings, forming a part of this specification, in which similar characters of reference indicate corresponding parts in all the views.

Figure 1 is a perspective view of an incandescent-lamp socket, showing my design. Fig. 2 is an inverted perspective view of the same, and Fig. 3 is a sectional plan view of the same.

The design in its entirety consists of a cylindrical body A, appearing at its ends with separated concentric bores B and C, the walls of which are screw-threaded, the body having its peripheral surface formed at opposite

sides with flat surfaces D and E, opening at their lower ends into the bore C, and from which surfaces extend inwardly and transversely into the body A the threaded bores F and G, vertical curved recesses H H' leading upwardly from the flat surfaces D and E to the top of the body A, and an internal vertical recess I appearing in the threaded wall of the bore C, below the flat surface D.

The leading feature of the design consists in the configuration made the subject of the accompanying illustrations.

Having thus fully described my invention, I claim as new and desire to secure by Letters Patent—

The design for an incandescent-lamp socket herein shown and described.

RUDOLPH MEYER.
